UNITED STATES PATENT OFFICE.

FRANK ANSLEY, OF SPOKANE, WASHINGTON.

GRINDING-MILL.

1,147,068.

Specification of Letters Patent. Patented July 20, 1915.

Application filed February 1, 1915. Serial No. 5,369.

To all whom it may concern:

Be it known that I, FRANK ANSLEY, a citizen of the United States of America, residing at Spokane, in the county of Spokane and State of Washington, have invented certain new and useful Improvements in Grinding-Mills, of which the following is a specification.

This invention pertains to grinding mills and has for its object to provide a mill which shall render a maximum amount of efficiency in grinding ores and consume a minimum amount of power.

To be more specific the invention pertains to that class of grinding mills where grinding rods are mounted in a drum and adapted to rotate, whereby by the rotation of the drum and the grinding together of the rods and the rock to be ground, the rock is pulverized and conveyed away by means thereto provided.

The class to which the invention pertains is well portrayed in my co-pending application filed January 14, 1915, under Serial of 1915 Number 2273.

A special object of the invention is to provide movable bearings in the heads of the drum whereby by the rotation of the drum the bundles of rods in the bearings will drop a distance together and fall over and against each other whereby the rock commingled with the rods is more effectively ground and pulverized.

A further object of the invention is to provide means whereby the length of the movements of the bearings carrying the ends of the bundles of rods may be regulated to give the desired length of drop to the rods as may be desired in crushing rock of different consistencies and under different conditions.

Other and further objects and novelties will be more fully hereinafter described, illustrated in the accompanying drawings and pointed out in the appended claims.

In the drawings, Figure 1, is a broken-away sectional view of a grinding mill of the character mentioned taken on the line 1—1 of Fig. 2, and embodying my invention, Fig. 2, is an end elevation of the mill with the plates covering the bearings carrying the ends of the rods removed and with the shaft supporting the drums sectioned. Fig. 3, is a sectional view taken on the line 3—3 of Fig. 2. Fig. 4, is a sectional view

taken on the line 4—4 of Fig. 2, and Fig. 5, is a sectional view taken on the line 5—5 of Fig. 2.

In a detail description, a mill of the character described is shown on the order of 60 my said co-pending application where an inner drum 10 and an outer drum 11 are supported by a horizontally arranged and transversely disposed shaft 12 with which they are adapted to rotate, the shaft 12 being supported as by brackets 13 having bearings 14 in which the shaft 12 is adapted to rotate. On the outer surface of the drum 11 are shown screens 15 through which the pulverized rock passes. A hopper 16 is 70 shown into which the rock is fed, there being an auger feed 17 at the base thereof to convey the rock through the wall 18 into the open space 19 from whence it passes in the direction of the arrows through the 75 opening 20 to a space 21 where the same is brought into contact with the bundles of rods 22.

Spaced apart in the vertical heads 23 of the outer drum 11 are openings 24 in which 80 are mounted plates 25 of a length to leave a portion of the spaces 24 unoccupied, the plates 25 being adapted to slide in the openings 24. Removable filling pieces 26 are provided and adapted to fit into the openings 85 24 to shorten or lengthen the slidable movement of the plates 25. Oblong openings 27 are provided in the plates 25 and are preferably provided with corrugated edges 28. Into these openings 27 the ends of the rods 90 22 have their supports and bearings.

The drum 11 is spaced around the drum 10 by an annular channel support 29 into which are secured the plates 33. The openings 24 in the plates are provided with an 95 annular flange 30 as an inside support for the slidable plates 25. A gasket or packing ring 31 is placed between the plate 25 and the flange 30 to make a dust proof joint. The wall 32 of the opening 27 supports the 100 rods 22 and the plate 33 secured to the plate 25 as by screws 34 support the rods 22 as against lateral movement and make complete the end inclosure of the drum 11.

In the practical operation of the mill and 105 of the construction herein claimed, when the shaft 12 is rotated as by the sprocket wheel 35 carrying the drums 10 and 11 with it and rock fed into the hopper 16 has found its way to the space 21 and in contact with 110

the rods 22, the plates 25 on the down-going side of the drum 11 in a counter clock-wise movement will slide in the space 24 striking against the insert 26 or the wall 24^a as the case may be and on the up-going side of the drum 11 will strike against the wall 24^b of the opening 24 crushing the mass of rods 22 into the rock and pulverizing the same, while the individual rods 22 will tumble over each other in the oblong openings 27 further pulverizing the rock, the corrugations 28 assisting in giving additional movement to the rods to further the pulverizing process. The inserts 26 are removed or any number may be added to properly regulate the length of the movement of the plates 25. A suitable packing 36 is placed between the ends of the plates 33 where they join together to make a dust proof joint.

20 What is claimed is,

1. A grinding mill comprising a drum mounted on a rotatable shaft and having slots in its end walls, slideable plates freely movable in said slots, and grinding rods having their ends freely supported in said plates.

2. A grinding mill comprising a drum mounted on a rotatable shaft and having slots in its end walls, slideable plates freely movable in said slots, grinding rods having their ends freely supported in said plates, and means for adjusting the length of the slideable movement of said plates.

3. A grinding mill comprising two concentric drums mounted on the same shaft and having an open space between them; the outer one of said drums having slots in its end walls; slideable plates movable in said slots and rods having their ends freely

supported in said plates and between said drums.

4. A grinding mill comprising two concentric drums mounted on the same shaft and having an open space between them; the outer one of said drums having slots in its end walls; slideable plates movable in said slots, rods having their ends freely supported in said plates and between said drums, and means for rotating said drums.

5. A grinding mill comprising two concentric drums mounted on the same shaft and having an open space between them; the outer one of said drums having slots in its end walls; slideable plates movable in said slots, rods having their ends freely supported in said plates and between said drums, together with means for adjusting the length of the slideable movement of said plates.

6. A grinding mill comprising two concentric drums mounted on the same shaft and having an open space between them; the outer one of said drums having slots in its end walls; slideable plates movable in said slots, rods having their ends freely supported in said plates and between said drums, means for rotating said drums, and means for adjusting the length of the slideable movement of said plates, such means comprising removable obstructions placed 70 in the path of said plates.

In testimony whereof I affix my signature in presence of two witnesses.

FRANK ANSLEY.
